POST-SUPPORTED LAMP

Josef Müller, Neheim-Hüsten, Germany, assignor to
Trilux-Lenze K.G., Neheim-Hüsten, Germany, a firm

Filed Aug. 3, 1962, Ser. No. 71,171

Claims priority, application Germany Apr. 19, 1962

Term of patent 7 years

(Cl. D48—31)

FIG. 1

FIG. 3

FIG. 1 is a perspective view of a post-supported lamp embodying my new design;

FIG. 2 is a perspective view thereof as seen from the bottom; and

FIG. 3 is a side elevational view of the lamp.

I claim:

The ornamental design for a post-supported lamp, as shown.
